UNITED STATES PATENT OFFICE.

HARRISON LORING, OF BOSTON, MASSACHUSETTS.

WIRE MAT FOR EXTRACTING OIL, &c.

SPECIFICATION forming part of Letters Patent No. 247,771, dated October 4, 1881.

Application filed May 25, 1880. (No model.)

To all whom it may concern:

Be it known that I, HARRISON LORING, of Boston, in the county of Suffolk and State of Massachusetts, have invented certain improvements in wire mats used in extracting juice from beets or other substances from which juice, oil, or other liquids are extracted by means of pressing, of which the following is a full, clear, concise, and exact description, reference being had to the accompanying drawings.

My invention consists, mainly, first, in the arrangement of the wires of which the mats are constructed so that they shall all radiate from the center, which gives to the mats great strength and the largest amount of conducting-surface, also conducting the liquid uniformly in the most direct manner from center to periphery; second, in introducing a seal-ring under the plunger to prevent the exuding of matter around the sides of the plunger.

In the drawings, Figures 1 and 2 are elevations, and Figs. 3 and 4 cross-sections, of two forms of mats, differing in the methods of leading the wires from the center.

In Fig. 1 I show a ring, *b*, made of iron, steel, or other metal, around which the wires are taken to be used where an open center is desirable. In other cases I use a circular plate, *C*, Fig. 2, with holes drilled around the edge, through which the wires are passed. The outer ring is formed in both cases by a welded metal hoop, *a a'*.

Fig. 5 shows a transverse section of a curb with mat, seal-ring, and plunger in place, *A* being the staves and hoops of the curb; *B*, the plunger; *C*, bottom of curb; *D*, section of mat; *E*, cross-section of seal-ring in its place under the plunger *E' E'*.

Fig. 6 is a half-plan view of the seal-ring. 40 This may be entirely separate and detached from the plunger or connected to the same in a manner to allow lateral motion, the outside of the ring being very nearly the same as the inside diameter of curb, whereas the plunger 45 must be made somewhat smaller, to allow for unsteady motion or inaccurate setting of the curb.

It is practically impossible to make the plunger fit snugly in the curb, and one feature of 50 my invention is the combination of the seal-ring with the curb and plunger, the effect being the same, so far as concerns preventing the material exuding between the plunger and curb, as if the plunger were a snug fit in the 55 curb, while at the same time all the disadvantages of having the plunger fit snugly in the curb are done away with by reason of the fact that the seal-ring is not fast to the plunger, but is capable of moving slightly under the 60 plunger during the pressing operation.

Another feature of my invention is forming the mat of a large number of wires arranged in bundles or layers twisted together, each bundle being also arranged radially and secured at the 65 center and at the circumference of the mat.

What I claim as my invention is—

1. The improved wire mat embracing in its construction a number of bundles or layers of wire, each bundle or layer being arranged radially and fast at the center and at the circumference of the mat, substantially as described. 70

2. In combination, the curb, the plunger, and the seal-ring, substantially as described.

HARRISON LORING.
